UNITED STATES PATENT OFFICE.

PAUL ACKERMAN, OF TORONTO, ONTARIO, CANADA, ASSIGNOR TO SEARS B. CONDIT, JR.

PARALLEL-FEEDER PROTECTION.

1,333,892.

Specification of Letters Patent. Patented Mar. 16, 1920.

Application filed December 24, 1917. Serial No. 208,572.

To all whom it may concern:

Be it known that I, PAUL ACKERMAN, a citizen of Switzerland, and a resident of Toronto, Province of Ontario, and Dominion of Canada, have invented an Improvement in Parallel-Feeder Protection, of which the following is a specification.

My invention relates to electrical distribution systems, and has particular reference 10 to the protection of parallel feeders associated with such systems.

It is common practice in distribution systems, where current is to be transmitted from a central power station to a distributing sub-station, to employ a number of parallel feeders extended between the power station bus bars and the substation bus bars 15 in order to provide continuity of operation upon the possible failure of one or more of 20 the parallel feeders.

Each of the parallel feeders is preferably normally arranged to have approximately the same operating characteristics; and all 25 of the feeders are arranged to carry equal loads. It sometimes happens that a fault occurs upon one of the parallel feeders of the system, and in such an event it is therefore desirable that the faulty feeder be isolated from the system without interfering 30 with the distribution of current throughout any of the other feeders of the system; and it is with means to accomplish this result that my invention is concerned.

As previously stated, the feeders are normally 35 adapted to carry equal currents. Upon the occurrence of a fault, such as a short, in any one of the feeders, the current flow in the faulty feeder is increased over that of the remaining parallel feeders, 40 and may become reversed in direction relative to the current flow in the remaining healthy feeders of the system.

Various protective systems have been conceived, making use of the relative increase 45 and reversal of current flow. Such a system, for instance, is disclosed in my Patent No. 1,192,724, dated July 25th, 1916.

In the distribution system illustrated in 50 said patent, any particular parallel feeder controlling circuit is governed by the condition existing in the parallel feeder to be governed, and by the condition of any two other parallel feeders of the system. This system has the disadvantage that if the two

parallel feeders associated with the parallel 55 feeder to be protected are removed from the system, the parallel feeder will be protected only against straight overloads, and not against relative reversal of current flow therein.

It is highly desirable that the removal 60 of one or more parallel feeders from the distribution system should not affect the operation of the protective devices guarding the remaining feeders from the effects of 65 faults developing within the feeders.

An object of my invention is in the provision of protective means for the parallel feeders of a distribution system associated 70 with all of the parallel feeders of the system, whereby the relative change of condition of any parallel feeder with respect to all of the other parallel feeders, serves to operate to remove the faulty feeder from the system.

By governing any particular feeder by all 75 the other feeders of the system, it may be seen that the removal from the system of any one or more feeders up to a predetermined number, does not affect the complete 80 control and protection of the particular feeder chosen.

The means whereby I accomplish the object of my invention is in the provision of 85 current transformers associated in the line of all the parallel feeders, and so connected with each other and with relays that, upon the normal condition of the system, in which each parallel feeder has the same 90 value of current flowing through it, and the system is balanced; the current transformers, or the effects of the current from the transformers upon the relays will be balanced, and the relays will thereby be unoperated; but upon the development of a 95 fault in any one feeder, resulting in an increased current flow in that feeder or a relative reversal of current flow in that feeder with respect to the remaining feeders; the increased or reversed current flow in the current transformer of the faulty feeder will 100 serve to unbalance the normally balanced protective system in which the relays are included, and serve to operate the relays to selectively cut out the faulty feeder.

There are a number of ways in which the 105 current transformers and relays may be connected between the parallel feeders of

the system to give the desired protection, all of which are intended to come within the scope of this invention.

For instance, inasmuch as the object of this invention is to connect the controlling or protective circuit of any particular feeder with all of the other parallel feeders, a possible scheme of connection is to connect a current transformer in the particular feeder with the current transformer of another parallel feeder, and to make connections between current transformers in the particular feeder with current transformers in the remaining parallel feeders, forming pairs of connected feeders between the particular feeder and all of the remaining feeders. If there are three parallel feeders in the system, numbered respectively 1, 2 and 3, and feeder 1 is the feeder to be protected; then there will be a connection between a transformer in line 1 and a transformer in line 2, and a separate connection between a second transformer in line 1 and a transformer in line 3.

Relays are associated in the connection between the pairs of transformers; and the connection between the transformers and the relays is such that, in the normally balanced condition of the circuit, the relays are ineffectively energized; but upon an unbalancing of the particular feeder, with respect to the other feeders with which it is connected, the relays will be operated; but both relays are arranged to be so connected as to collectively control the particular parallel feeder, and therefore, both relays must be operated to cut out the particular parallel feeder from the system.

While the connection above described illustrates the principle of the system, in that pairs of connections are made between the feeders, and protective relays arranged in said connections, yet it is possible to combine the relays and the current transformers in the feeders to form a certain minimum number, which will completely fulfil the requirements of the object of the invention.

In practice, there are two general schemes of connections between the current transformers associated in the parallel feeder circuits and the relays. It is possible to connect the transformers in series with the coils of the relays and employ differential relays, in which condition the magnetic flux in the relays will normally be bucking each other, and the relays are thereby normally ineffectively energized; and it is possible to connect the current transformers of the parallel feeder system in series; and connect the coils of the relays, employing this time non-differential relays, in shunt across the transformers, in which connection the relays are normally ineffectively energized. Both schemes of connection are old in the prior

art, and are interchangeably employed where the type of transformer and other associated instruments seems to justify the use of one system rather than the other.

In the figures, Figure 1 illustrates diagrammatically a protective system showing the general scheme of connection, embodying my invention, associated with three parallel feeders.

Fig. 2 illustrates a protective system for three parallel feeders in which a minimum number of relays and current transformers are used, the relays being connected in series with the transformers.

Fig. 3 illustrates diagrammatically the scheme of connection for three parallel feeders employing series connected current transformers and shunt connected relays.

Fig. 4 is a system of Fig. 3 in which a minimum number of transformers and relays are employed.

Fig. 5 illustrates a protective system for four parallel feeders, employing the series scheme of relay connection and a minimum number of transformers and relays.

Fig. 6 is a protective system for four parallel feeders, employing the shunt scheme of relay connection and a minimum number of transformers and relays.

As shown in Fig. 1, the parallel feeders 10, 11 and 12 are connected to the bus bar 14, which may represent the sub-station end of the distribution system. Each parallel feeder has a switch 15, in its circuit which when operated serves to disconnect its particular parallel feeder from the bus bar 14; and each switch has associated with it the tripping coil 16, which is arranged to be governed by the protective relays to be hereinafter described.

The control circuit for any parallel feeder is associated with all of the other parallel feeders, and therefore line 10 is associated with line 11 and line 12; the condition of said lines 11 and 12 being a measure of the condition of line 10. Also line 11 is associated with line 10 and line 12, in which case the condition of said lines 10 and 12 form a measure of the condition of line 11; and also line 12 is associated with lines 10 and 11, in which connection lines 10 and 11 form a measure of the condition of line 12. As there are three lines, there are

$$2+1=3$$

pairs of connections which can be made between the current transformers of the parallel feeders.

In Fig. 1 current transformers 17 are arranged in lines 10 and 11, and the current coils or secondaries thereof are respectively connected to the coils 18 and 19 of a differential relay 20. A second current transformer 17', in line 10, and a current trans-

former 17' in line 12, are also respectively connected to the coils 18 and 19 of the differential relay 21.

A second transformer 17' included in the line 11, and a second current transformer 17 included in line 12, are respectively connected to the coils 18 and 19 of a differential relay 22.

The relays 20, 21 and 22 are provided with two sets of contacts 23 and 24, which are adapted to be simultaneously closed upon the operation of the relay; and the connection between the circuits including the switch tripping coils 16 is such that two relays must be simultaneously closed in order to energize the tripping coils of the switch of a particular feeder, in order that said feeder may be removed from the system.

In the normal operation of the system, the coils 18 and 19 of the differential relays 20, 21 and 22, in the pairs of connections between the feeders of the system, are equally and oppositely energized, and consequently all of the relays are in a non-operative position.

Upon the occurrence of a fault in feeder 10, for instance, the resulting increase or reversal of current flow in the transformers 17 and 17', connected in said feeder, relatively to the current flow in the transformers in the remaining parallel feeders of the system, serves to unequally energize the coils 18 of the differential relays 20 and 21, or to cause them to act cumulatively to cause the simultaneous operation of said relays to close the contacts 23, which completes the operating circuit for the tripping coil 16 and the switch 15 of the feeder 10 thereby operates to disconnect said feeder from the bus bar 14.

The closing of contacts 24 of the relays 20 and 21, upon the operation of said relays to isolate the feeder 10 from the system does not operate to complete the circuit for the tripping coil for any other feeder switch, inasmuch as both of the separate trip coil circuits, controlled by the contacts 24 of the relays 20 and 21, are also governed by the relay 22 connected between the two normal or healthy feeders 11 and 12, and which is thereby unaffected by the faulty condition of the feeder 10.

If the fault occurs in feeder 11 instead of in feeder 10, then the relays 20 and 22, connected in the connections between parallel feeders 11 and 10, and 11 and 12 respectively, operate to close contacts 24 of the relay 20, and 23 of relay 22, to conjunctively control the operation of the trip coil for the switch 60 in feeder 11, to isolate said feeder from the bus bar 14.

The trip coil circuits for the switches in the remaining and healthy feeders 10 and 12 will be maintained open at the contacts controlled by relay 21 which is unaffected

by the conditions of current flow caused by the fault in feeder 11.

The operation of the protective system to isolate the feeder 12 from the distribution system upon the occurrence of a fault in said feeder, is in all respects similar to that described in connection with feeders 10 and 11.

Fig. 2 illustrates a simplified arrangement of the protective circuits of Fig. 1, embodying the scheme of pairs of connections between the parallel feeders, in which the feeders 10, 11 and 12 have but the current transformers 17 associated therewith, which transformers are independently connected with any three differential relays 20, 21 and 22. In the connection shown, current transformer 17 in line 10 is connected to the coils 18 of relays 20 and 21. Transformer 17 in line 11 is connected to the coil 18 of differential relay 22 and the coil 19 of relay 20. Transformer 17 of line 12 is connected to the coil 19 of relay 22 and the coil 19 of relay 21. Considering feeder 10, the two relays 20 and 21 are adapted for its protection, and are governed by the feeder 11, the transformer of which is connected to the coil 19 of relay 20, and by feeder 12 the transformer of which is connected to the coil 19 of relay 21. The other pairs of connections between the remaining feeders are similarly connected to the coils of the differential relays.

In the normal and balanced condition of the feeders, referring particularly to feeder 10, the flux resulting from the energization of both coils 18 and 19 in both relays 20 and 21 will be balanced, and the relays will therefore not be energized to close the contacts 23 and 24, which are connected as in Fig. 1, to the tripping circuits of the switches 15 in the feeders. Upon the occurrence of a fault in feeder 10, which results in an overload or a reversal of current flow therein relative to the other two feeders, the coils 18 of the relays 20 and 21 will become energized in greater proportion than the coils 19 of said relays, which are connected respectively to the transformers in feeders 11 and 12 and which are normally energized, or in which, at least, there is no relative reversal of current flow; and thereby both relays will be simultaneously operated to complete the connection, through contacts 23 of the relays, with the tripping coil 16 to cause the opening of the switch 15 in the feeder 10, to thereby isolate the feeder from the circuit. Upon a fault occurring in any other feeder, the same condition of affairs will be set up, and the proper relays will be effectively energized to remove the faulty feeder from the system.

Fig. 3 represents schematically the connections between the current transformers and the relays in which the current trans-

formers of the pairs of parallel feeders are connected in series; and the relays are connected in shunt across the connections between the pairs of current transformers. 5 The system shown in Fig. 3, so far as operation is concerned, is exactly similar to the system shown in Fig. 1, with the exception that in Fig. 3 there is a series connection of current coils, and shunt connection of relays. 10 As here shown in Fig. 3, the current transformer 17 in feeder 10 is connected in series with the transformer 17 of feeder 11. A second transformer 17' in feeder 10 is connected in series with a transformer 17' in 15 feeder 12, thereby connecting line 10 with all of the other feeders of the system. A transformer 17' in feeder 11 is connected in series with a transformer 17 in feeder 12, and feeder 11 is thereby connected with all 20 of the other feeders in the system, and line 12 is also connected with all the other feeders in the system.

Relays 25, 26 and 27 are connected respectively in shunt across the connections 25 between the transformers connecting feeder 10 with 11, 10 with 12 and 11 with 12. In the normal and balanced condition of the feeders there is no voltage drop across the relay coils; and consequently, the relays are 30 not operated. However, upon an occurrence of a fault in feeder 10, for instance, the current in transformers 17 and 17' in said feeder will become greater than the current in transformer 17 of feeder 11 and 35 in the transformer 17' of line 12; and therefore the relays 25 and 26 will become effectively energized and operate to close the contacts 23 controlled by said relays to energize the tripping coil 16, and cause the 40 isolation of the faulty feeder 10 from the system. The occurrence of a fault in any other feeder will cause a pair of relays to be operated in a similar manner to remove the faulty feeder from the system.

45 In Fig. 4 is shown a simplified scheme of connections of the protective system of Fig. 3, the operation of which is exactly similar to the operation of the system shown in Fig. 3. As here shown, the current transformers 17 in the parallel feeders 10, 11 and 12 are connected in series with each other. The relays 25, 26 and 27 are connected in shunt across the three transformers 17 in the feeder circuits, and, as here shown, relays 25 and 26, in series, are connected across transformer 17 in line 10; relays 25 and 27, in series, are connected across the transformer 17 in line 11; and relays 26 and 27 are connected in series across the 50 current coil 17 in line 12. It is seen that with this scheme of connection, any particular feeder is connected with all the other feeders.

Two relays must be operated to control 60 the controlling circuit for any particular

feeder system. In the operation of the system shown in Fig. 4, in the normal and balanced condition of the feeders, there is an equal current flow in each of the current transformers in the feeders; and, consequently, the relays 25, 26 and 27, connected across these transformers will not be operated, due to the absence of a difference of potential at the points to which the relays are connected. If, however, a fault 75 develops in feeder 10, for instance, the current in the transformer 17 in said feeder becomes greater than the current in the remaining transformers 17 of the protective system, or relatively reversed in direction; 80 and a difference of potential is set up across the secondary of said transformer which operates to energize relays 25 and 26 connected in shunt across said transformer, and the relays are consequently operated to complete the circuit, including the tripping coil 16 of the switch 15 governing the feeder 10 to operate said switch to isolate the feeder from the system. Upon the occurrence of a fault in any other feeder of the system, 90 said feeder will be cut out of the system in a manner similar to that described in regard to feeder 10.

Fig. 5 shows a simplified scheme of connections for a protective system involving 95 four parallel feeders, in which the current transformers are connected in series with the relays governing the tripping circuits. The relays in this case are differential 100 relays.

Inasmuch as there are four parallel feeders to be protected, there must be employed

$$3+2+1=6$$

105 relays, which represents the number of pairs of connections which may be made; and which is the minimum number of relays that may be employed to completely protect a system comprising four feeders, 110 and which is connected between the parallel feeders of the system in accordance with the invention. Considering the case of any one feeder, there are three remaining feeders to the system, and there must of necessity be three relays, each of which respectively has one coil connected to a transformer in one of the three remaining feeders, and all of which have a coil connected with the transformer in the particular 115 feeder in question. Three of the relays must therefore be conjointly operated to cause the isolation of the faulty feeder from the system.

Fig. 6 represents the protection of four 120 parallel feeders in which the series connection of current coils and the shunt connection of relays is employed. Inasmuch as there are three combinations of one line, considering any particular parallel feeder 125

against the remaining three feeders, it follows that there must be provision for three taps of three relays corresponding to one line. With one transformer per line, there is available but two such taps, and it is therefore necessary to employ at least two transformers for each line in order to provide the requisite number of taps to properly connect the three relays required to completely protect the line in question.

As here shown, feeders 10, 11 and 12 have each a transformer 17, which are connected in series. A second transformer 17' in feeder 10 is separately connected in series with a second current transformer 17' in feeder 12, and with a transformer 17 in feeder 13. A second transformer 17' in line 11 is connected in series with a transformer 17' in feeder 13, which connection is independent from the two previous sets of transformer connections. Relays 28, 29 and 31 are connected to points between the transformers 17 in feeders 10, 11 and 12. Relays 30 and 33 are connected across the connections between transformers 17' and 17 in feeders 10, 12 and 13 respectively, and relay 32 is connected across the connections between the current coils 17' in feeders 11 and 13.

30 By the arrangement of transformers and relays shown, any particular feeder is connected with all the remaining feeders, and the operation of three relays serves to control the controlling or tripping circuit for the switch of the particular feeders chosen.

In the operation of the protective system illustrated, in the normal condition of equal current flow in all of the current transformers in the parallel feeders, there is no potential difference between the points between the transformers to which the relays are connected, and consequently the relays are not operated. Upon the occurrence of a fault, say in feeder 10, a potential difference is set up across the transformer 17 in said feeder, and relays 28 and 29 are energized, and operate to close the contacts 23 and 24 controlled thereby. The operation of said relays alone does not, however, suffice to cause the energization of the tripping coil 16 of the switch 15 of the feeder 10.

Due to the fault, the potential across transformer 17' in feeder 10, which transformer is connected with transformers 17' and 17 respectively in feeders 12 and 13, serves to energize relay 30, and the operation of said relay 30 serves to complete the tripping circuit and cause the isolation of the faulty feeder 10 from the system.

60 No other tripping circuits will be affected inasmuch as other relays, arranged to be unoperated upon the occurrence of a fault in feeder 10, must also be operated to control the tripping circuits for the other feeders.

65 A similar operation of the proper relays

occurs upon the occurrence of a fault in any other feeder of the system.

As a general proposition, it may be stated that with n feeders, the total number of relays to adequately protect all the feeders is

$$(n-1) + (n-2) + \text{etc.} \dots [n - (n-1)]$$

and the number of relays that must be simultaneously operated to selectively remove any faulty feeder from the system is $n-1$.

If there are six feeders to be protected, for instance, then the total number of relays to adequately protect all of the feeders is

$$5+4+3+2+1=15$$

80 relays, and the number of relays that must be simultaneously operated to remove a feeder from the system is one less than the total number of feeders in the system; or five relays.

85 In the cases above cited, a single phase line is illustrated. If a three phase line, or any multi-phase line is employed, the number of relays must be duplicated for each phase. The diagrams represent one end of the feeder system, which may be the end connected with the sub-station bus bars. The other end of the feeder may be provided with exactly the same equipment of relays, to isolate the faulty feeder from the system at that end. The total number of relays in any system will always correspond to the total possible number of pairs of connections between feeders, and the total number of relays in series to trip one switch to 100 isolate the corresponding feeder from the system will be equal to the total number of pairs of connections between one feeder and the remaining parallel feeders.

105 In the lines above described, it has been assumed that the feeders have approximately the same characteristics. If one or more of the feeders are of different characteristics, then the windings of the relays, or the transformers, associated with such feeders is so arranged as to compensate for such difference.

I claim:

1. In an electrical distribution system comprising a plurality of parallel feeders connected through switches with buses, connections between any particular feeder and all other feeders in the system, a relay in each connection, a tripping circuit for each feeder, each relay arranged to govern a plurality of tripping circuits, and means to cause the relays in the connections between a particular feeder and all other feeders to operate to selectively and conjointly control the tripping circuit for the particular feeder to isolate said feeder from the bus upon the occurrence of an abnormal current condition in said feeder.

120 2. In an electrical distribution system comprising a plurality of parallel feeders

connected through switches with buses, inductive connections between any particular feeder and all other feeders in the system, a relay in each connection, a tripping circuit for each feeder, each relay arranged to govern a plurality of tripping circuits, and means to cause the relays in the connections between a particular feeder and all other feeders to operate to selectively and jointly control the tripping circuit for the particular feeder to isolate said feeder from the bus upon the occurrence of an abnormal current condition in said feeder.

3. In an electrical distribution system comprising a plurality of parallel feeders connected through switches with buses, connections between the feeders to form a combination of pairs of connected feeders between any particular feeder and all other feeders of the system, a relay in the connection between each pair of connected feeders, a tripping circuit for each feeder, means to cause each relay to control a plurality of tripping circuits, and means to cause the relays in a particular combination to operate to conjointly control a particular tripping circuit upon the occurrence of an abnormal current condition in the corresponding feeder to thereby isolate said feeder from the bus.

4. In an electrical distribution system comprising a plurality of parallel feeders connected through switches with buses, inductive connections between the feeders to form a combination of pairs of connected feeders between any particular feeder and all other feeders of the system, a relay in the connection between each pair of connected feeders, a tripping circuit for each feeder, means to cause each relay to control a plurality of tripping circuits, and means to cause the relays in a particular combination to operate to conjointly control a particular tripping circuit upon the occurrence of an abnormal current condition in the corresponding feeder to thereby isolate said feeder from the bus.

5. In an electrical distribution system comprising a plurality of parallel feeders connected through switches with buses, inductive connections between the feeders to form a combination of pairs of connected feeders between any particular feeder and all other feeders of the system, a relay in the connection between each pair of connected feeders, a tripping circuit for each feeder, means to cause each relay to control two tripping circuits, and means to select for operation certain relays to conjointly control the tripping circuit of a particular feeder to isolate said feeders from the bus upon the occurrence of an abnormal current condition in said feeder.

6. In an electrical distribution system comprising a plurality of parallel feeders

connected through switches with buses, inductive connections between the feeders to form a combination of pairs of connected feeders between any particular feeder and all other feeders of the system, a relay in the connection between each pair of connected feeders, certain of said relays being common to a plurality of such combinations, a tripping circuit for each feeder, the relays included in a particular combination operable to conjointly control the tripping circuit for the particular feeder of the combination and in conjunction with relays of other combinations to control tripping circuits of other combinations, and means to cause the relays of a particular feeder combination to operate to conjointly control the tripping circuit of the particular feeder to isolate such feeder from the bus upon the occurrence of an abnormal current condition therein.

7. In an electrical distribution system comprising a plurality of parallel feeders connected through switches with buses, transformers in said feeders, connections between the secondaries of said transformers to form a combination of pairs of inductively connected feeders between a particular feeder and all other feeders of the system a relay in the connection between each pair of connected feeders, the number of relays being one less than the number of possible combinations, certain of said relays forming a part of more than one combination, a tripping circuit for each feeder, the relays of a particular combination arranged to control the feeder circuit of the feeder forming the combination with all other feeders, and means to cause the relays of the particular combination to operate to conjointly control the particular feeder to disconnect it from the bus upon the occurrence of an abnormal current condition in said feeder.

8. In an electrical distribution system comprising a plurality of parallel feeders connected through switches with buses, transformers in said feeders, tripping circuits for said feeders, a plurality of relays each arranged to control two tripping circuits, two or more relays arranged to control each tripping circuit, and connections between said transformers, and relays to select certain of said relays for operation to conjointly control the tripping circuit for a particular feeder to isolate said feeder from the bus upon the occurrence of an abnormal current condition in said feeder.

In testimony whereof, I have signed my name to this specification, in the presence of two subscribing witnesses.

PAUL ACKERMAN.
